UNITED STATES PATENT OFFICE.

GEORGE WILLIAM BELDAM, OF EALING, ENGLAND.

DESIGN FOR A PNEUMATIC TIRE FOR VEHICLE-WHEELS.

49,792.

Specification for Design.

Patented Oct. 24, 1916.

Application filed June 27, 1916. Serial No. 106,272. Term of patent 14 years.

To all whom it may concern:

Be it known that I, GEORGE WILLIAM BELDAM, a subject of the King of England, residing at Ealing, in the county of Middlesex, England, have invented a new, original, and ornamental Design for Pneumatic Tires for Vehicle-Wheels, of which the following is a specification.

Referring to the accompanying drawings, Figure 1 is a plan view of part of a pneumatic tire illustrating the new design; and Fig. 2 is a perspective view of the same.

The design consists of a tread having V-shaped portions extending from each edge of same, and within it more or less rectangular recesses with studs within same, the studs being practically flush with the running surface of the tread.

In the drawings *a* designates the tread, and *b* the V-shaped projecting parts thereof.

c designates the rectangular recesses in the tread extending all around the tire, and *d* are the studs within same.

I claim:

The ornamental design for a pneumatic tire, for vehicle wheels substantially as shown and described.

In testimony whereof I have signed my name to this specification in the presence of the two subscribing witnesses.

GEORGE WILLIAM BELDAM.

Witnesses:

S. J. EARL,
ERNEST R. TUCK.
